UNITED STATES PATENT OFFICE.

MAX RACHLIN, OF BROOKLYN, NEW YORK.

GUTTER HANGER.

Application filed September 20, 1924. Serial No. 738,884.

To all whom it may concern:

Be it known that I, MAX RACHLIN, a citizen of Russia, and resident of Brooklyn, in the county of Kings and State of New York, have invented certain new and useful Improvements in Gutter Hangers, of which the following is a specification.

The present invention relates to improvements in eaves-trough hangers, and more particularly to hangers made of sheet metal.

The main object of the invention is to provide a gutter hanger, including a bar extending transversely of the gutter, said bar being disposed wholly outside of the said gutter so as not to obstruct the flow of water therein.

Another object of the invention is to provide a gutter hanger having means made, preferably, integral therewith for preventing the said hanger from shifting longitudinally upon the gutter.

A further object of the invention is to so construct the transversely extending bar of the hanger that it prevents the accumulation of ice, snow or water thereon.

A still further object of the invention is to provide a gutter hanger of the type mentioned which is simple in construction, efficient in operation, durable in use, strong and capable of manufacture on a commercial scale or, in other words, one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a side elevation of a gutter hanger constructed in accordance with the present invention, the gutter being shown in position thereon; Fig. 2 is a top plan view of the said hanger, in its flat state; Fig. 3 is a section taken through the bead por-

tion of the gutter and the adjoining elements of the hanger; Fig. 4 is a section taken on line 4-4 of Fig. 1; and Fig. 5 is a section taken on line 5-5 of Fig. 1, on a larger scale.

In the drawings, the numeral 10 indicates a roof gutter, the outer edge of which is provided with a bead 11, as usual in constructions of this type, while its inner edge 12, adjacent the wall of the building, is plain. For supporting this gutter in proper relation to the roof 13 of the building, there is provided a plurality of hangers, spaced apart a suitable distance, each of 14, said hangers including a strap portion 14, which surrounds transversely the gutter, and a bracket 15, the latter being attached to said strap and the roof. The strap 14 is made, preferably, of a single piece of sheet metal, and includes a curved gutter-embracing portion 16, having a hook-shaped bend 17 at one of its ends, said bend fitting over the bead 11 of the gutter and merging into a bar section 18, which extends horizontally 19 and transversely of the gutter. The opposite end of this bar is bent over the plain edge 12 of the gutter, as shown at 20 in Fig. 1 of the drawings, and is provided with a slot 21 in its bight. Through this slot 22 is extended the free end 23 of the gutter-embracing portion 16 of the strap, and is thence bent downwardly into contact with the rear face of the said bent portion 19, as shown at 24.

The bar section 18 is of inverted V-shape in cross-section, it including sloping sides 25, bounded by sloping ends 26. The bar section is disposed wholly above, that is to say outside of the gutter, its end 26 adjoining the hook-shaped section 17 being extended below the bar section downwards into the gutter, as shown at 27, and joining at a sharp angle the said hook-shaped section, as clearly shown at 28. In a similar manner is the end 24 adjoining the bend 19 extended downwards into the gutter, as shown at 29, joining at a sharp angle the said bend 19, as indicated at 30.

The bracket 15 is joined with the bar 18, preferably, by a rivet 31. The outer end of this bracket is secured by nails 32, or otherwise, to the roof from which the rain water is to be carried off. The inner end of the bracket is substantially U-shaped in transverse cross-section, as shown at 33 in Fig. 5 of the drawings, the said U-shaped

end fitting over a hollow boss 32, which is formed at the ridge 33 of the bar 18, the said hollow boss accommodating the lower head 34 of the rivet 29 (Fig. 5). The hollow boss is, preferably, formed by means of a drawing press whereby that section of the bar 18 on which the boss is formed is considerably strengthened. This compensates for the weakening, that is the result of punching a hole in the said bar, through which the rivet 29 is extended.

Immediately below the hook-shaped bend 17 the gutter embracing portion 16 of the strap is provided with a projection 35 on its inner face. This projection is obtained, for instance, by making an indentation by a suitable tool, such as, for instance, by a punch. The projection is, preferably, sharp pointed, whereby it forms a notch 36 in the gutter when the gutter embracing portion 16 of the hanger is bent around the said gutter, the material of which the hanger is formed being of a heavier gage than that of which the gutter is made. The projection, being disposed within the said notch, prevents the gutter hanger from moving longitudinally upon the gutter. The said projection also aids in shaping the hook-shaped section 17 and in maintaining the same in contact with the bead 11 throughout its length.

Inasmuch as the bar 18 of the hanger is disposed wholly outside of the gutter, it obviously does not form an obstruction to the flow of water and other material within the gutter. As mentioned above, both the sides and the ends of the bar slope, whereby accumulation of ice, snow and water thereon is effectively prevented.

It is obvious that while herein the projection 35 has been described as being made integral with the strap of the gutter hanger, it may be in the form of a separate element, for instance a rivet or like construction, attached to the strap. It is also obvious that while herein the said projection has been described in combination with a gutter

hanger of a specific type, it may be used generally on all strap gutter hangers.

What I claim is:—

1. A gutter hanger comprising a bar extending transversely of the gutter and provided at its outer end with a hook-shaped section fitting over the bead of the gutter, the opposite end of said bar being provided with a bend adapted to rest on the opposite edge of the gutter, said bend being provided with a slot, a strap member forming a continuation of said hook-shaped section tightly embracing the underface of the gutter and adapted to be drawn through said slot, said bar being of inverted V-shape in transverse cross-section, its sloping sides being bounded by sloping ends, said bar being disposed wholly above said gutter, one of said sloping ends being extended downwards into said gutter and merging at a sharp angle with said hook-shaped section, and the other one of said sloping ends being also extended downwards into the gutter and merging at a sharp angle with said bend.

2. A gutter hanger comprising a bar extending transversely of the gutter and provided at its outer end with a hook-shaped section fitting over the bead of the gutter, the opposite end of said bar being adapted to be fixed to the opposite edge of the gutter, a strap member forming a continuation of said hook-shaped section tightly embracing the underface of the gutter and engageable with the opposite end of said bar, and a projection on the inner face of said strap member adjacent said hook-shaped section, said projection being forced into the gutter when said hanger is fitted thereto.

3. In a gutter hanger according to claim 2, said projection being made integral with said strap member.

Signed at New York, in the county of New York and State of New York, this 17th day of September, A. D. 1924.

MAX RACHLIN.
